UNITED STATES PATENT OFFICE.

HENRY W. PLEISTER, OF WESTFIELD, NEW JERSEY, ASSIGNOR TO HENRY B. NEWHALL.

BOLT-ANCHOR.

1,155,614.

Specification of Letters Patent.

Patented Oct. 5, 1915.

Original application filed January 20, 1915, Serial No. 3,328. Divided and this application filed April 16, 1915. Serial No. 21,635.

To all whom it may concern:

Be it known that I, HENRY W. PLEISTER, a citizen of the United States, and a resident of Westfield, in the county of Union and State of New Jersey, have invented certain new and useful Improvements in Bolt Anchors, of which the following is a specification, taken in connection with the accompanying drawings, which form a part of the 10 same.

This application is a division of my companion application Ser. No. 3,328 filed January 20, 1915.

My invention relates to bolt anchors, and 15 one in which both the shield and the bolt or screw contact directly with the walls of the support in which they are mounted.

More particularly it relates to a one part 20 shield which may be manufactured and sold separately as an article of manufacture.

Previous to my invention it has been the common practice to have shields and anchors with two or more expanding members between which the bolt or screw was mounted, the different members of the shield or anchor being forced apart as the bolt or screw was inserted between them. In such bolt anchors the threads of the screw or bolt engage simply with the different members 25 of the shield or anchor and do not engage directly with the walls of the orifice. In the old practice the shields are formed of at least two members, and the anchors are provided with at least two tines or forks, it 30 being understood that in the trade an "anchor" has an integral head from which extends two or more tines. Ordinarily the trade use the term "anchor" when referring to ductile material in which the male 35 screw threads of the expanding member will cut their own coöperating female screw threads in the softer material of the anchor.

By my invention I omit entirely one of the 40 expansive members and save all the expense incident to its manufacture, handling and shipping.

By my invention the screw threads of the bolt or screw engage directly with the walls of the orifice as well as with my expansion 45 shield.

In my invention the complete "bolt anchor" comprises a shield member and the expanding member whether that be a bolt or screw.

50 I form my shield of ductile material,

which allows the screw threads of the bolt or screw to cut their own coöperating threads in the shield.

I have shown in the accompanying drawings several illustrative embodiments of my 60 invention, but of course it is to be understood that my invention is not to be confined simply to the forms illustrated. In these drawings the same reference numerals refer to similar parts.

Figure 1 is a longitudinal vertical section through a support and the work supported showing one form of my bolt anchor formed of some comparatively soft ductile material which is softer than the material of which the bolt is formed so that the latter will cut its own screw threads; Fig. 2 is a perspective view of the ductile shield shown in Fig. 1; Fig. 3 is a longitudinal vertical section of a modified form of ductile shield 70 which is provided with a rib in which the bolt will cut its own coöperating screw threads; Fig. 4 is a perspective view of the shield shown in Fig. 3; Fig. 5 is a longitudinal vertical section through a support and the article supported showing a tapered substantially semi-cylindrical one part shield formed of some ductile material into which the threads of the bolt will cut their own coöperating female threads. In this figure the hole in the support is at right angles to the face of the support and a beveled washer is shown to compensate for the inclination of the bolt head; Fig. 6 is a perspective view of the ductile shield illustrated in Fig. 5; Fig. 7 is a transverse vertical section through a channel beam and its support showing my ductile bolt anchor adapted to coöperate directly with a flange of the channel beam so as to positively hold it to its support; Fig. 8 is a view similar to Fig. 5 except that in this figure the hole or aperture in the support is at an angle to the face of the wall; Fig. 9 is a side elevation of a modified form of ductile shield provided with lugs. In this figure the support and the work are shown in vertical section and a wood screw is shown coöperating with the shield; Fig. 10 is a fragmentary vertical section showing a modified construction in which one lug is used rather than two as shown in Fig. 9; Fig. 11 is a side elevation of a further modified form of shield in which the body member has a double inclined surface, the exterior surface being provided with trans-

verse ribs of progressively increasing height from the front to the rear of the shield to compensate for the taper of the exterior surface of the body member. This 5 form is the same as the others except that it is a little more economical to manufacture in that less ductile metal is needed to form the body member of the shield; Fig. 12 is a cross section on line 12-12 of Fig. 9 10 showing the lugs in dotted and full lines.

In all forms of my invention the bolt or screw, whichever is used, contacts directly with the surface of the hole in the support, and, in addition, in this particular invention, cuts its own coöperating female screw threads in the comparatively soft material of the shield.

To use my invention, a hole 3 is drilled in any support 1 of masonry, brick, terra cotta, 20 concrete, wood or any other suitable support, for the insertion of the ductile shield 4, Figs. 1 and 2. In the form of my invention shown in these figures, the shield 4 is a semi-cylindrical member provided with 25 an axial bore 5; its ends 6 and 7 are substantially of the same cross section. The lag bolt 2, for example, may be the screw threaded coöperating member which is used as the expanding member so that its male 30 screw threads 8 will cut their own coöperating screw threads in the comparatively soft material of the shield. The taper of the lag bolt, or wood screw, if one is used, serves to expand the ductile shield into a 35 firm contact with a portion of the wall of the hole while the lag bolt, or other expanding member, directly bears upon other portions of the wall of the hole. In this manner the work 9 is held firmly and securely 40 to the face 10 of the support 1.

In some instances I may provide a shield 11, Figs. 3 and 4, with a longitudinally extending rib 12 in which the screw threads 8 of the lag bolt 2 will cut their own coöperating screw threads, see Fig. 3. Preferably 45 this longitudinally extending rib 12 is formed at the same time as the body of the shield 11. In practice I preferably, though not necessarily, form my ductile shield 13 50 with an inclined surface 14 so that the end 15 of the shield 13 which is last to be inserted in the hole, and which lies adjacent to the face of the wall, will be of less area than the other end 16 of the ductile shield. 55 I have shown the simplest form in Figs. 5, 6, 7 and 8, and shown also, further modifications, in Figs. 9 and 11. By arranging the ductile shield with one end thinner than the other, or of less area, the inclined surface 60 face 14 is formed and it is up this inclined surface that the wood screw or lag bolt 2 is screwed home to hold the work to the support. In this screwing home of the screw or bolt its male threads bear upon the wall of the hole and also cut their own coöperat-

ing female screw threads in the ductile shield. In Fig. 8 I have shown the bolt anchor formed of the ductile shield 13, and the lag bolt 2 mounted in a hole 17 which is drilled or otherwise made in the support 1 70 at an angle to the face 18. If this hole is drilled at the proper angle it will exactly compensate for the inclination of the lag bolt 2 due to it following the inclined surface 14 of the ductile shield 13. In such a 75 case the work 9 will be brought up flush to the face 18 of the support, and the head 19 of the bolt 2 will bear firmly against the work 9.

In case the longitudinal axis of the hole 80 20 is drilled in the support 1 at right angles to the face 18 I preferably though not necessarily, use a beveled washer 21 between the head 19 of the bolt 2 and the work 9, Fig. 5. Without such a washer only a portion 85 of the head 19 would engage with the work 9. This inclination of the head of the bolt, when the hole in the support is substantially at right angles to the face, can be put to many practical advantages. 90

I have shown for example in Fig. 7 a base or support 22 having a hole 23 drilled substantially at right angles to the face 24 of the support 22 which may be of concrete, stone, or any other material. In this figure 95 I have shown a bolt anchor comprising the shield 13 and the lag screw 2 mounted in the opening 23 so that the head 19 will be inclined with relation to the face 24 of the support. When the work to be supported 100 or held has an inclined surface, web, flange, 105 lug or other member, this inclination of the head of the bolt will exactly coöperate with such an inclined member of the work to be supported or held. In Fig. 7 I have shown 105 the work to be held or supported as a channel member 25 having an inclined flange 26 with which the head 19 of the bolt 2 exactly coöperates when it is screwed home in the opening 23 of the support 22. In other 110 words, the work supported or held, has itself some inclined surface or member which will exactly coöperate with the head of the bolt when it is inclined with relation to the face of the support. While I have shown 115 for example a channel member 25 it is of course obvious that the work may be an I-beam, T-rail, rail, structural member, electrical apparatus having an inclined lug or member or any other structure having an 120 inclined holding surface. In such a construction as illustrated, for example, in Fig. 7, the holding capacity of the bolt anchor will be increased for the stress exerted upon the head 19, of the bolt will be partly shear 125 and partly tension. In this form of my ductile bolt anchor the lag bolt 2, or other expanding screw member, will center itself upon the inclined surface 14 and travel in 130 a line parallel with the axis of the shield, as

it will be held in that position by the curvature of the hole in the support. In this form the male screw threads 8, 8 will cut their own female screw threads in the face 14 of the shield and will bear directly upon the material of the support whatever that may be. Of course if the material of the support 1 be brick, cinder concrete, or wood or any material softer than that of the bolt, 10 more or less deep female screw threads will be formed in the support by the male threads 8, 8. In this form my complete bolt anchor comprises the lag or other bolt 2 and the ductile shield 13.

15 In the constructions I have previously described I have shown my invention in the simplest form. Preferably though not necessarily, I form the shield member with some means which will prevent the accidental disengagement of the shield and expanding member. This is an advantage in case it is desirable to ship or store the bolt anchors. The means which I preferably employ to hold the bolt and shield together 20 also furnishes a support or bearing for the bolt while under the shearing strains.

In Figs. 9, 10 and 11, I have shown one preferred form of my ductile bolt anchor in which one or more retaining means as 30 lugs are used to hold the ductile shield and expanding member together. In Fig. 9 my ductile shield 126 is preferably provided with an interior tapered bore 27 in which the male threads of the wood screw 28, or 35 lag bolt as the case may be, cut their own female threads. In this form I preferably provide the shield 26 with some retaining means to hold the expanding member from accidental disengagement in handling, storing, 40 shipping for example. The retaining means which I preferably employ are one or more integral lugs 29, 29 which are preferably cast at the same time that the shield 26 is cast. These lugs are preferably cast open as shown in dotted lines in Fig. 12 and then bent as shown in full lines in that figure. In Fig. 9 the ductile shield 126 is provided with four such lugs. One such lug 30, Fig. 10, however, may be used 45 if desired being preferably cast as shown in dotted lines and then bent up as shown in full lines in this figure.

50 Preferably, though not necessarily, the bolt anchor is inserted in the opening 31 of the support 1 with the lugs downward and the cross ribs 32 of the shield 126 adapted to bite into the upper portion 33 of the support 1. I preferably so locate the bolt anchor in the opening so as to compensate 55 for shearing strains due to supporting the work 9. The lugs 29, 29 serve as a bearing for the screw 28, so that any shearing strains due to supporting the work 9 will tend to force the male threads 34, 34 into closer 60 contact with the female threads that they

cut in the shield 126. That is the greater the shearing strain, firmer will be the contact or engagement between the male threads of the screw or bolt and the shield which will cause the transverse ribs 32, 32 of the shield to bite all the more into the wall 33, of the support to make a firmer and stronger expansion.

70 It is of course to be understood that if the shield 126 is put into a hole drilled at right angles to the face of the wall that a bevel washer may be used the same as in the other figures. In this Fig. 9 the hole is at an angle to the face 35 of the support 1 in which case it is not necessary to use such a bevel washer.

75 It is of course to be understood that in all forms of my invention the bolt anchor may be sold as an article of commerce, or the ductile shield alone may be so sold, the other member of the bolt anchor being supplied by the jobber, retailer or user.

80 To economize in the amount of metal used in the ductile shield I may, in some cases, Fig. 11, form a shield 36 having the inclined surface 37 to coöperate with the lag or other bolt or screw and I provide transverse ribs 38, 38 of varying height, those at the inner end, which will be the end farthest in the hole, being of greater height than those nearer the other end of the shield. This construction simply saves metal by making the grooves 39, 39 between the different transverse ribs 38, 38 of greater depth, at 85 the inner end, than in the other forms.

100 In addition to the marked economy in manufacture and ease of application of my bolt anchor and its advantage in directly co-operating with an inclined engaging surface on the work to be supported or held, it also prolongs the life of the support, if that support happens to be wood. In light work, for example, in securing storm sash and awnings, a regular wood screw is often replaced in the same hole, the threads of the screw on practically every new insertion cutting new threads in the wood which disintegrates the fiber of the wood and destroys its holding capacity. In such light work by my invention, only a portion of the surface of the hole would be engaged on each insertion of the screw, so that the life of the fiber of the wood would be prolonged.

115 Not only this, but the wedging action of my bolt anchor would compress or condense any partly comminuted fiber of the wood in the hole which would give the expansion bolt a strong hold even though the screw be repeatedly reinserted in the same hole.

120 Having thus described my invention in connection with the illustrative embodiments thereof to the details of which I do not desire to be limited except as required by the scope of the appended claims, what is claimed as new and what it is desired to 125

secure by Letters Patent is set forth in the appended claims.

What I claim as my invention and desire to secure by Letters Patent is:—

5 1. An article of manufacture comprising a shield member having an open side, said member being formed of ductile material to permit a bolt to cut its coöperating female threads in the open side of the shield and at 10 the same time engage directly with the wall of the support.

15 2. An article of manufacture comprising a shield member having an inclined surface and an open side, said member being formed of ductile material to permit a bolt to cut its coöperating female threads in the open side of the shield and at the same time engage directly with the wall of the support.

20 3. An article of manufacture comprising a shield member having an open side, said member being formed of ductile material to permit a bolt to cut its coöperating female threads in the open side of the shield, and at 25 the same time engage directly with the wall of the support and means to normally hold the shield and bolt together.

30 4. An article of manufacture comprising a shield member having an inclined surface and an open side, said member being formed of ductile material to permit a bolt to cut its coöperating female threads in the open side of the shield, and at the same time engage directly with the wall of the support and means to normally hold the shield and bolt 35 together.

40 5. A bolt anchor comprising in combination an expanding member and a one part ductile shield adapted to partly surround the expanding member.

45 6. A bolt anchor comprising in combination an expanding member and a one part ductile shield having a bore said shield adapted to partly surround the expanding member.

50 7. A bolt anchor comprising in combination an expanding member and a one part ductile shield having an inclined surface said shield adapted to partly surround the expanding member.

8. A bolt anchor comprising in combina-

tion an expanding member, and a one part ductile shield substantially semi-cylindrical in cross section at one end.

9. A bolt anchor comprising in combination an expanding member, and a one part 55 ductile shield, substantially semi-cylindrical in cross section at one end, the other end being of less area in cross section.

10. A bolt anchor comprising in combination an expanding member, and a one part 60 ductile shield, substantially semi-cylindrical in cross section at one end, the other end being of less area in cross section and said ductile shield being provided with a bore.

11. A bolt anchor comprising in combination an expanding member, and a one part 65 ductile shield, substantially semi-cylindrical in cross section at one end, the other end being of less area in cross section and said ductile shield being provided with an inclined bore.

12. A bolt anchor comprising in combination an expanding member and a one part 70 ductile shield adapted to partly surround the expandable member and means to secure the expandable member and shield together.

13. A bolt anchor comprising in combination an expanding member and a one part 75 ductile shield adapted to partly surround the expandable member and means integral 80 with the shield to secure the expandable member and shield together.

14. A bolt anchor comprising in combination an expanding member and a one part 85 ductile shield adapted to partly surround the expanding member and one or more lugs on the shield adapted to hold the shield and expandable member together.

15. A bolt anchor comprising in combination a screw threaded expanding member, 90 and a ductile shield, the screw threads of the expanding member adapted to engage at the same time the ductile shield and the wall of the aperture in which the bolt anchor is mounted.
